UNITED STATES PATENT OFFICE.

JOHN RICHARDS, OF SAN FRANCISCO, CALIFORNIA.

METAL-DRILLING MACHINE.

SPECIFICATION forming part of Letters Patent No. 261,044, dated July 11, 1882.

Application filed January 17, 1882. (No model.)

To all whom it may concern:

Be it known that I, JOHN RICHARDS, a citizen of the United States, residing at San Francisco, in the county of San Francisco and State 5 of California, have invented certain new and useful Improvements in Metal-Drilling Machines, of which the following is a specification, reference being had therein to the accompanying drawings.

10 This invention relates to machines for drilling metal; and it consists in a new and simple mechanism for feeding and adjusting the spindle of such machines, and in so arranging such mechanism that it can be inclosed in the 15 spindle-frame, as hereinafter more fully set forth.

In the annexed drawings, which fully illustrate the invention, Figures 1 and 2 represent front and side elevations, respectively, of a 20 metal-drilling machine embodying my invention. Fig. 3 is an enlarged section on the line $x-x$ of Fig. 1, and Fig. 4 is a plan and section on the line $y-y$ of Fig. 3.

Like letters indicate like parts in the several views.

A is the main frame of the machine, and B is a table adapted to be adjusted vertically to any desired position. The main frame A has a forward-projecting arm, at the end of which 30 is a hollow cylindrical frame or casing, a , in which is supported the drilling-spindle b and its operating mechanism. This drilling-spindle is actuated by the bevel-gear wheels $c c'$ and cone-pulleys C in the usual manner. To move 35 the drilling-spindle b up and down, the hand-wheel d is turned accordingly. This wheel, by means of its shaft d' , operates the upper pair of bevel-gears, $e e'$, which correspond in general to the gears $c c'$ inverted. On the upper horizontal wheel, e' , is formed a sleeve, f , which is supported in bearings $h h$. At the 40 upper end of this sleeve, which curves inward at g , is formed, on its inner face, a series of screw-threads fitting corresponding threads 45 on a sleeve, m , which is attached to and forms a continuation of the spindle b , but does not revolve with it. At the top of the inner sleeve, m , there is a notched extension, m' , (shown in plan in Fig. 4,) which notch engages with a rib

or feather, p , in the interior of the cylindrical 50 case or frame a , and thus prevents the inner sleeve, m , from turning when the outer sleeve, f , is revolved. The spindle b is suspended by a through-rod, n , that passes up through the sleeve m , and is held by nuts o at the top. This 55 rod n is fastened to the spindle b and revolves with it. The gear-wheel e' and sleeve f are sustained by a distance-collar, s , that is counterbored into the two horizontal wheels e' and c , so that the spindle b will have a continuous 60 bearing throughout its range.

The operation of these feeding devices will be obvious from the construction illustrated in the drawings. When the hand-wheel d is turned the sleeve f is caused to revolve, and 65 the sleeve m and spindle b are moved up or down accordingly.

The spindle b can be readily removed by unscrewing the nut o , and all the parts in the casing a can be taken out by removing the 70 foot-bearing t , which is held by screws $w w$, as shown in Fig. 3.

Having thus described my invention, what I claim as new, and desire to secure by Letters Patent, is—

75 1. In a metal-drilling machine, the combination, with the casing a , having feather p , the spindle b , provided with rod n , having nut o , and the threaded sleeve m , surrounding said rod and provided with notched projection m' , 80 engaging with the feather p , of the threaded sleeve f , gears $e e'$, and hand-wheel d , substantially as described.

2. In a metal-drilling machine, the combination, with the casing a and spindle b , inclosed 85 therein, of the threaded sleeve m , having a loose connection with said spindle, the threaded sleeve f , having gear e' , the gear e and hand-wheel d for actuating the sleeves f and m to feed the spindle, and the gears $c c'$ and 90 cone-pulley C for rotating said spindle, substantially as described.

In testimony whereof I affix my signature in presence of two witnesses.

JOHN RICHARDS.

Witnesses:

E. R. STEVENS,
D. J. PADDOCK.
